E. YOUNGERMAN

DETACHABLE ANTISLIPPING MEANS

Filed Oct. 22, 1921

Inventor:
Edgar Youngerman
By Earl M. Sinclair
Atty

UNITED STATES PATENT OFFICE.

EDGAR YOUNGERMAN, OF DES MOINES, IOWA.

DETACHABLE ANTSLIPPING MEANS.

Application filed October 22, 1921. Serial No. 509,592.

The object of this invention is to provide improved means for preventing slipping or skidding of a shoe when worn by a person engaged in running, pulling and the like, such as a player of football, base-ball, tug-of-war and similar games.

A further object of this invention is to provide improved means for securing a calk device to a shoe in such manner that it can readily, quickly and conveniently be removed and replaced relative to the shoe.

A further object of this invention is to provide improved means for bracing a calk device along the shank of a shoe sole.

A further object of this invention is to provide means for constructing engaging hooks integral with and operated by supporting members of scissors type.

My invention consists in the construction, arrangement and combination of elements hereinafter set forth, pointed out in my claim and illustrated by the accompanying drawing, in which—

Figure 1 is an inverted plan of a shoe showing my device mounted thereon as required for practical use. Figure 2 is a side elevation of the calk device detached from the shoe. Figure 3 is a front elevation of the device.

In the construction of the device as shown the numerals 10, 11 designate metal bars or arms, relatively thin and wide, which are bent laterally adjacent to their ends and cross each other, scissors fashion, in recumbent positions and on oblique lines. The crossing portions 12, 13 or joints of the bars are provided with holes adapted to receive a pivot bolt 14 or rivet whereby the bars are pivotally connected. Forward end portions of the bars 10, 11 are bent upwardly and recurved slightly to form hooks 15, 16 adapted to engage margins of a shoe sole in front of the ball or widest portion thereof. Rear end portions of the bars 10, 11 are extended substantially straight and in parallel planes and extremities thereof, are bent laterally and upwardly and recurved slightly to form hooks 17, 18 adapted to engage side margins of a shoe sole at the rear

of the ball or widest portion thereof. The hooks 17, 18 and members carrying the same are adapted to embrace the shoe sole and extend across it substantially coincident with the line of demarcation between the tread and shank of the sole. Calks 19 are formed on and turned downwardly relative to the forward end portions of the bars or joint portions 12, 13 and said calks preferably have their width in substantial alinement transversely of the sole. Ears 20, 21 are formed on and bent downwardly relative to the inner, adjacent margins of the rear end portions of the bars 10, 11. The ears 20, 21 preferably are in substantially parallel planes adjacent to and on opposite sides of the median line of the shoe and are apertured in registration to receive a bolt 22. The bolt 22 preferably is provided with a nut 23 on one end and a head 24 on the other end, said head being formed with a shoulder engaging the adjacent ear and itself made angular in cross-section and adapted to be engaged and rotated by a socket wrench such as a skate key, not shown, of common form. A brace or strap 25 is formed on and constitutes a rearward extension of the bar 10 and is shaped and adapted to extend along and in contact with the outer marginal portion of the shank of the sole. The tread portion of the sole 26 of the shoe is designated by the numeral 27 and the shank thereof by the numeral 28.

In practical use the device is tightened upon or released relative to the sole of the shoe by manipulation of the bolt 22, the effect of which is immediately to contract the hooks 17, 18 on or expand them relative to the sole and, remotely, acting through the crossed pivoted members 12, 13, to contract the hooks 15, 16 on or expand them relative to the forward portion of the sole. Normally engagement of the device with the earth surface is by way of the calks 19 but under some conditions and circumstances the ears 20, 21 and pivot bolt 14 supplement the anti-slipping functions of the calks by engagement with such surface.

I claim as my invention—

A detachable anti-slipping means, comprising a pair of bars pivoted together scissors-like, hooks on the ends of said bars, integral calks on said bars, apertured ears 5 formed on and projecting from the rear portions of said bars, a bolt extending through the apertures of said ears whereby the device may be expanded and contracted, and an extension brace formed on and extending substantially in the line of the rear 10 portion of one of said pivoted bars.

Signed at Des Moines, in the county of Polk and State of Iowa, this 21st day of September, 1921.

EDGAR YOUNGERMAN.
